UNITED STATES PATENT OFFICE.

EDWARD P. DANDRIDGE, OF PHILADELPHIA, PENNSYLVANIA.

CONVEYING MEANS.

1,380,886.

Specification of Letters Patent. Patented June 7, 1921.

Application filed December 28, 1920. Serial No. 433,636.

To all whom it may concern:

Be it known that I, EDWARD P. DANDRIDGE, a citizen of the United States, residing at Philadelphia, in the county of Philadelphia and State of Pennsylvania, have invented 5 certain new and useful Improvements in Conveying Means, of which the following is a specification.

One object of my invention is to provide 10 an improved device for use in restaurants, hotels, etc., for the purpose of conveying food from the kitchen to the dining room and for the purpose of delivering orders from the waiters in the dining room to the 15 chef in the kitchen so as to facilitate the service.

Another object is to so construct my improved device that it will include means 20 operative by someone in the kitchen for actuating a carriage; there also being present improved means for signaling the person in the kitchen when to start or stop the conveying means both in the outward movement therefrom from the kitchen and 25 the inward movement thereof from the dining room to the kitchen.

Another object is to make the device of my invention of a durable and practical construction and so that it can be operated 30 and controlled without causing confusion.

These objects, and other advantageous ends which will be described hereinafter, I attain in the following manner, reference being had to the accompanying drawings in 35 which

Figure 1 is a side elevation of my improved device,

Fig. 2 is a top plan view of the device shown in Fig. 1,

Fig. 3 is an elevation of the right hand end of said device,

Fig. 4 is a transverse sectional elevation taken on the line 4—4 of Fig. 1,

Fig. 5 is a transverse sectional elevation 45 taken on the line 5—5 of Fig. 1, and

Fig. 6 is an enlarged fragmentary perspective view showing certain of the parts of my invention.

Referring to the drawings, 7 represents an 50 elongated frame structure which includes side beams 8, cross beams 9 and supporting legs 10 all secured together to form a rigid structure; the right hand end portion being adapted to be located in the kitchen while 55 the portion to the left of said latter mentioned portion is adapted to extend length-

wise into the dining room and may be of any length suitable to the length of the dining room. The frame 7 forms a support for two rails 11 which provide a track upon 60 which is adapted to roll a carriage 12.

Two shafts 13 and 14 are mounted in suitable bearings adjacent opposite ends of the frame 7 and these shafts respectively have grooved pulleys 15 and 16 thereon. The 65 shaft 14 which, in the arrangement above specified will be positioned in the kitchen, has a hand crank 17 thereon which when turned will rotate the pulley 16. A cable 18 has one end hooked to the forward portion 70 of the carriage 12 and from this end the cable passes over and under the pulley 15, then lengthwise of the frame between the beams 8, then upwardly around the pulley 16 and is hooked at 19 to the rear end of 75 the carriage 12. The cable 18 includes an adjustable turnbuckle 20 which can be moved to take up slack in the cable as is clearly obvious from the construction shown in Figs. 1 and 2.

From the above construction it is clearly seen that if the hand crank 17 is rotated in one direction, the carriage 12 will move toward the right hand end of the frame and if the hand crank is moved in an opposite 85 direction, the carriage 12 will move toward the left hand end of the frame. The carriage 12 supports a tray 21; said tray being secured and projecting over the top surfaces of side rails 22; said side rails having 90 a removable pin connection 23 with the tops of the beams 8. Thus any attempt of the carriage or tray to tilt will be resisted by the top surfaces of the side rails 22. With this construction if the side rails 22 become 95 soiled they can be readily removed from the frame 7 by lifting them so that the pins 23 thereon become detached from the frame. The bottom run 24 of the cable 18 has secured thereto an enlargement or ring 25 pref- 100 erably of non-metallic material such as tough leather, fiber or the like which has a certain degree of resilience. The main frame 7 has a lever 26 pivotally mounted thereon; said lever having an eye or hole 27 through 105 which the bottom run 24 of the cable 18 passes. This hole 27 is of less diameter than the diameter of the ring 25 so that when the ring 25 reaches the lever 26 it cannot pass through the hole 27 and will therefore swing the lever 26 on its pivot 28 against the action of a spring 29; said

spring serving to hold the lever 26 in its normal position. The pivot pin 28, in the construction as illustrated, has another part 30 of the lever secured thereon which is movable into and out of engagement with an alarm device, such for example as a bell 31 as shown in Fig. 6. Thus when the ring 25 moves the lever 26, the portion 30 of said lever will strike the alarm device 31 and 10 effect an audible alarm, notifying the person operating the crank 17 to stop turning the shaft 14; it being noted that the ring 25 will move the lever 26 to cause said alarm when the carriage 12 reaches its full travel toward 15 the left hand end of the frame.

As a means of signaling the operator within the kitchen, when the waiter desires to have the carriage returned, such for example as when the waiter desires an order 20 of food, I attach a cord 32 on the side of the frame; said cord being attached to a hammer 33 which is pivoted between its ends as shown at 34. This hammer is normally held away from a projection 35 by 25 means of a spring 36. Thus then the cord 32 is pulled from any position within the length of the frame, the hammer will be swung to strike the projection 35; thereby making a noise informing the operator to 30 move the carriage toward the right hand end of the machine; it being noted that said hammer and projection are preferably positioned so as to be located in the kitchen.

With my improved apparatus it will be 35 readily understood that the carriage can be moved outwardly to convey food and move inwardly either to return soiled dishes or the waiter can place a written order upon the tray 21 so that it will be conveyed 40 into the kitchen after which the chef can make up the order and return the same on the carriage to the waiter. This prevents the necessity of the waiter walking backwardly and forwardly from the dining room 45 to the kitchen and facilitates the dispensation of the food. If a waiter desires the carriage 12 to stop at a particular place within the length of the frame, he can signal the operator through the medium of the 50 cord 32, for example, two pulls of the cord 32 will cause the hammer 33 to strike the projection 35 twice; thus producing a signal, and the signal for returning the carriage can be produced, for example, by a single 55 pull of the cord 32.

While I have described my invention as taking a particular form, it will be understood that the various parts of my invention

may be changed without departing from the spirit thereof, and hence I do not limit myself to the precise construction set forth, but consider that I am at liberty to make such changes and alterations as fairly come within the scope of the appended claims. 60

Having thus described my invention, what 65 I claim as new and desire to secure by Letters Patent is:—

1. A device of the character described including an elongated supporting structure having side rails spaced apart; a track below the tops of said rails; a carriage on said track and having a portion movable between said side rails; and a tray secured to said carriage and having projecting portions directly above the tops of the side rails; substantially as described. 70 75

2. A device of the character described including a supporting structure having a track thereon; a carriage movable on said track; pulleys respectively located adjacent 80 opposite ends of the track; a cable passing around said pulleys and having its opposite ends in one run thereof secured to the carriage; means for turning said pulleys whereby the carriage can be moved backward and 85 forward along the track; and a signaling member having a hole therein through which a run of said cable can pass, said cable having an enlarged portion thereon not capable of passing through said hole whereby the 90 signaling device will be operated to inform a person of the position of the carriage with respect to the supporting structure; substantially as described.

3. A device of the character described including a supporting structure having a track thereon; a carriage movable on said track; pulleys respectively located adjacent 95 opposite ends of the track; a cable passing around said pulleys and having its opposite 100 ends of one run between the pulleys secured to the carriage; means for turning said pulleys whereby the carriage can be moved backward and forward along the track; and side rails located at opposite sides of said 105 carriage and being detachably connected to said supporting structure; substantially as described.

In testimony whereof I have signed my name to this specification in the presence 110 of two subscribing witnesses.

EDWARD P. DANDRIDGE.
